UNITED STATES PATENT OFFICE.

JAMES F. MOORE, OF VALLEY STATION, KENTUCKY.

ASPHALT DISTRIBUTOR.

Application filed March 29, 1923. Serial No. 628,663.

To all whom it may concern:

Be it known that I, JAMES F. MOORE, a citizen of the United States, residing at Valley Station, in the county of Jefferson and State of Kentucky, have invented certain new and useful Improvements in Asphalt Distributors, of which the following is a specification.

This invention relates to road making machinery, and has special reference to an asphalt distributor and pulverizer.

One important object of the invention is to improve the general construction of devices of this character.

A second important object of the invention is to provide a device of this character having novel means for feeding the asphalt to a crushing device.

A third important object of the invention is to provide an improved device of this character having a novel arrangement of primary and secondary crushing means.

A fourth important object of the invention is to provide an improved device of this character having a novel arrangement of feed bin.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Fig. 1 is a side elevation of the improved asphalt distributor and pulverizer.

Fig. 2 is a longitudinal vertical median section therethrough.

Fig. 3 is a plan view thereof.

Fig. 4 is an enlarged detail section of the primary crusher.

Fig. 5 is an enlarged detail perspective view of one of the teeth of the primary crusher.

Figure 6 is a detail perspective showing the manner of connecting the chain 21 and plate 28.

In the embodiment of the invention herein illustrated, there is provided a lower rectangular frame 10, which is supported on suitable ground wheels 11 at the front and back thereof. Extending diagonally upward from the front of this frame is a pair of rails 12, the upper ends of which connect with a pair

of horizontal rails 13 supported by brace frame members 15. On the rear portion of the bottom frame 10 is carried a suitable motor 16, which is here shown as an ordinary internal combustion motor, and this motor serves to drive the various parts of the apparatus. These rails 12 and 13 support the sides 17 of a bin, which sides have inwardly directed bottom flanges 18 whereon rests a movable bin bottom 19, which is pivoted to a fixed bin bottom 20 at its rear end, and which, at its forward end, is provided with a chain and hook 21. Mounted on the upper rails 13 is a winding drum 22, which is driven from the motor 16 by means of a suitable sprocket chain 23. Mounted to travel on the rails 12 and 13 is a carriage 24 having wheels or rollers 25, which engage said rails. This carriage 24 rests, in its lowered position, against an abutment 26 carried by the bottom ends of the rails 12. On this carriage is pivotally mounted a hopper 27, the hopper being pivoted to the lower or front end of the carriage, and this end of the carriage being provided with a plate 28 having a suitable opening therein for engagement by the hook 21. The carriage 24 has at its upper or rear end a transverse plate 29 which connects the sides of said carriage. Wound on the drum 22 is a cable 30, which is connected to the hopper 27 at the upper rear portion thereof, as clearly shown in Fig. 1.

Leading downwardly from the fixed bottom 20 is a chute 31 for conveying material from the bin to the lower end of a belt conveyor 32, which leads upwardly through a suitable housing 33. In the chute 31 is located a breaker wheel 34, which includes a hollow cylindrical drum 35 having a plurality of openings 36 therein arranged in staggered relation to each other. The breaker teeth each consist of a body portion 37, a bent shank 38 which projects through a respective opening 36, and has its end engaged within the drum 35 against the inner side thereof, and a tail 39 which is secured to the drum by a suitable bolt 40. Thus these teeth may be readily detached or replaced in the event of wear or breakage.

Beneath the upper end of the conveyor 32 is a crusher consisting of a plain wheel or drum 41, and a corrugated or serrated wheel or drum 42, these two being placed sufficiently close together to thoroughly pulverize any material passing between them.

- Beneath the secondary crusher is a delivery chute 43 which terminates in a swinging delivery spout 44 projecting downwardly and rearwardly from the body of the machine.
- 5 The secondary breaker or crusher and the conveyor are actuated by means of a suitable sprocket chain 45, and gearing 46, while the primary breaker is actuated by means of a sprocket chain 47 and gearing 48.
- 10 In operation, large lumps of asphalt are placed in the hopper 27, which is preferably of such capacity as to hold one-half of the ordinary wagon load. The winding drum is then set in motion whereupon the hopper 15 tilts downwardly from the position shown in full lines in Fig. 1 to the dotted line position in that figure. Continued winding of the cable 30 moves the hopper and its carriage up the rails 12, and along the rails 13.
- 20 At the same time, the hook and chain 21 are engaged with the plate 28 so that the bottom of the bin folds up behind the hopper as it moves upward and rearward. By means of this construction, any material spilling over 25 the sides of the hopper will drop on this bottom and thus, when the bottom has its forward end raised, will move down to the delivery chute 31. After the hopper and its carriage have been pulled fully up on the 30 rails 13, the winding drum 22 may be reversed, a suitable controlling lever 49 being provided for the purpose of controlling such winding drum, while a similar lever 50 controls the breakers and conveyor. Upon 35 reversal of the winding drum, the hopper tilts downward to the position shown in dotted lines in Fig. 2, and thus dumps its entire load into the bin. The primary breaker then acts upon the lumps in the bin, and breaks 40 them up in small sizes after which they pass up the conveyor and are crushed by the secondary breaker or crusher, passing from thence through the chute 43 in finally commutated form to be spread on the roadway 45 or be placed in suitable receptacles for conveyance elsewhere.
- There has thus been provided a simple and efficient device of the kind described and for the purpose specified.
- 50 It is obvious that minor changes may be made in the form and construction of the invention without departing from the material spirit thereof. It is not, therefore, desired to confine the invention to the exact form 55 herein shown and described, but it is desired to include all such as properly come within the scope claimed.
- Having thus described the invention, what is claimed as new, is:
- 60 1. In a device of the kind described, a wheel supported frame, rails on said frame extending upwardly and then rearwardly from one end of the frame and other rails 65 extending rearwardly in a substantially horizontal direction from the upper end of the

first rails, a carriage traveling on said rails, a dumping hopper mounted on said carriage, means to move said carriage on said rails, a bin under the rearwardly extending portion of said rails, said bin including a movable 70 bottom member hinged at its rear edge to a fixed portion of the bin, and means for connecting the free edge of said bottom member to said carriage.

2. In a device of the kind described, a 75 frame including upwardly and rearwardly extending rails and other rails extending rearwardly in a substantially horizontal direction from the upper ends of the first rails, a skeleton carriage mounted to move along 80 said rails, a hopper pivoted at its bottom to the lower and forward end of said carriage, a winding drum at the rear end of said second rails, a cable connecting the upper end 85 of said hopper with said winding drum, said hopper being adapted to swing freely between the sides of the carriage whereby the hopper may be inverted in position through the carriage, and a bin beneath the second mentioned rails to receive the contents of 90 said hopper.

3. In a device of the kind described, a 95 frame including upwardly and rearwardly extending rails and other rails extending rearwardly in a substantially horizontal direction from the upper ends of the first rails, a skeleton carriage mounted to move along 100 said rails, a hopper pivoted at its bottom to the lower and forward end of said carriage, a winding drum at the rear end of said second rails, a cable connecting the upper end 105 of said hopper with said winding drum, said hopper being adapted to swing freely between the sides of the carriage whereby the hopper may be inverted in position through the carriage, a bin beneath the second mentioned rails to receive the contents of said 110 hopper, said bin including a bottom hinged at its rear edge and provided with a hook for engagement with the carriage whereby to cause the bottom to swing upwardly and rearwardly as the carriage moves upwardly and rearwardly.

4. In a device of the kind described, a 115 wheel supported frame, rails on said frame extending upwardly and then rearwardly from one end of the frame, a carriage traveling on said rails, a dumping hopper mounted on said carriage, means to move said carriage on said rails, a bin under the rearwardly extending portion of said rails, said bin including a movable bottom member 120 hinged at its rear edge to a fixed portion of the bin, and means controlled by the movement of the carriage to hopper dumping position for raising the free edge of said bottom member.

In testimony whereof I affix my signature.

JAMES F. MOORE.
